UNITED STATES PATENT OFFICE.

EGBERT PERRY SARTELL, OF ST. CLOUD, MINNESOTA.

CAR-HEATER AND PIPE-CONNECTION.

SPECIFICATION forming part of Letters Patent No. 417,447, dated December 17, 1889.

Application filed May 20, 1889. Serial No. 311,412. (No model.)

To all whom it may concern:

Be it known that I, EGBERT PERRY SARTELL, of St. Cloud, in the county of Stearns and State of Minnesota, have invented certain new and useful Improvements in Car-Heaters and Pipe-Connections; and I do hereby declare that the following is a full, clear, and exact description of the invention, which will enable others skilled in the art to which it appertains to make and use the same, reference being had to the accompanying drawings, and to the letters of reference marked thereon, which form a part of this specification.

15 My invention relates to certain improvements in attachments for steam, hot-air, or hot-water car-heaters, and for other purposes, such as for air-brakes or the like.

The object of the invention is to provide 20 an improved apparatus and arrangement whereby the use of flexible hose or tubing at the coupling-connection between the cars is dispensed with and rigid metallic pipes substituted therefor, having improved coupling 25 or connecting heads on their ends, said pipes being capable of lateral, vertical, and longitudinal play; and a further object is to so inclose said pipes and couplings that the heat radiated therefrom will not be wasted, but 30 conveyed back into the car. These objects are accomplished by, and my invention consists in, certain novel features of construction and in combinations of parts more fully described hereinafter, and particularly pointed 35 out in the claims.

Referring to the accompanying drawings, Figure 1 is a detached plan view of the interior of the box or chamber attached to one end of a car. Fig. 2 is a vertical longitudinal 40 section of the device of Fig. 1. Fig. 3 is a view, similar to Fig. 2, of a modification. Fig. 4 is a longitudinal section of a pair of connecting-heads about to engage, the valves in the same being shown opened to avoid 45 confusion of parts, as if the heads were in tight engagement. Fig. 5 is a detail perspective of a coupling-head. Figs. 6 and 7 are details.

In the drawings the reference-letter *a* indicates the steam or hot-air or other heating pipes. Two are shown in the present instance

extending into and through the car and downwardly through the bottom of the car at its opposite ends into boxes or chambers *b*, secured to the bottom of the car at the opposite ends thereof and projecting forwardly from said ends. The heating pipe or pipes extend horizontally and longitudinally through said boxes and project from the front ends of the same beyond the end of the car. On its projecting end each pipe is provided with the half member of a pipe-coupling, each coupling head or member consisting of an outwardly-flaring head *c*, secured to the end of its respective pipe. The end of the head is provided with a semi-spherical recess *d*, and the edge of the head around said recess is provided with the elastic packing-ring *e*, secured in a groove in said edge. This recess *d* is partially filled by a semi-spherical block *f*, secured or formed therein at an angle, with one side or edge projecting therefrom, so that the flat inner face *g* of the semi-sphere will be located in said recess at an angle, leaving a corresponding recess or socket beside it. This 70 inner face is provided with one or more annular packing-rings secured thereon and surrounding a central port *h*, communicating with the interior of the heating-pipe by passage *i*, extending through the flaring head. A 75 hinged check-valve *j* is located in said head to close said port by the back-pressure when the connection or coupling is released, and the valves of a pair of connecting or coupling members are automatically opened, when coming together, by means of arms or a hinged ring *k*, located at the exterior of the port and connected with the valve, so that when the two heads come in contact the hinged rings or arms will force back the valves and open 80 the ports.

From the foregoing it will be readily seen that when the connection is made the surrounding edges of the two flaring heads tightly engage with the flat inclined faces *g* 90 and their packing-rings in contact and with the ports therein registering, and the projecting ends of the blocks *f* fitting snugly in the recesses beside the faces *g* of the opposite member, thereby forming a perfect and 100 tight compound joint, as the inner joint between the faces *g* is within and at an angle

to and crossing the plane of the outer surrounding joint between the edges of the flaring heads, and the projecting portion of each member fitting into the corresponding socket 5 of the opposite member prevents independent slipping or play at the joint. The tighter the cars are coupled the closer will be the connection, as the connection is made by the abutting car.

- 10 The horizontal portions a' of the heating pipes a in the chambers b and carrying the coupling-heads are connected with the pipes in the car by the vertical portions and elbows l and the coupling-elbows l' , in the outer ends 15 of which the inner ends of said pipe-sections a' loosely extend, so as to be longitudinally movable therein and to receive packing to form a tight joint therewith, and the coupling-heads are yieldingly held to their limit 20 of outward movement by the coiled springs m , interposed between and securely fastened to the lugs or projections n on the pipe-sections a' and stationary lugs n' in the chamber. These springs hold the coupling-heads 25 yielding and yet tightly together when the coupling is made.

A box or casing o surrounds the pipe-sections carrying the coupling-heads, which sections pass through apertures in the ends of 30 the box, and the two coupling-heads at each end of the car are thereby held against independent lateral or vertical movement. The top and bottom of this box is provided with guides or tracks p , against which the blocks 35 q on the pipes bear and move when the pipes are moved longitudinally, and this box is yieldingly held in position to allow lateral and vertical play of the coupling-heads by coiled springs r , interposed loosely between 40 plates s , bearing against the sides and top and bottom of the box o , and corresponding adjustable plates t , located at the top and bottom and sides of the chamber b , said plates bearing against set-screws w , by which the 45 tension of the springs r can be varied; the side plates t adapted to move in ways, as shown, the connections between the pipe-sections carrying the coupling-heads, and the main pipes in the car being formed by coupling sleeves and joints, so as to allow the pipe-sections universal and also longitudinal play, as described, against the tension of the 50 springs, which yield to the motion of the car.

The front ends of the chambers b are provided with supplemental ends or flexible spring-bumpers c' , provided with openings which register with openings in the front ends of the chambers b , for the passage of the coupling-heads and pipes carrying the same, 55 and these bumpers are loosely secured to the ends of said chambers by flexible sides or casings d' , and are yieldingly held at their limit of outward movement by the expandible springs e' , preferably secured to plates attached to the ends of the chambers and the supplemental ends. The face of each bumper 60 and the opening therein is surrounded by the

packing f' . Thus it will be seen that when two cars come together and are coupled the bumpers c' engage and are compressed, and 70 the pipes are automatically connected and coupled and communication established between the interiors of the two chambers b , which interiors are shut out of communication with the outer air by the flexible bumpers c' and packing f' , and hence all the heat radiating from the coupling and pipes outside of the car will be retained and passed into the car through the openings and registers. 75

In Fig. 3 a modification is shown, in which but one large coil-spring tapering toward the ends is used, embracing the pipes and bearing against the plates t , and the ends of the spring are secured to surround four plates h' , 80 each plate having two apertures through which the pipes extend, and each pair of plates are rigidly secured together, clamping blocks or nuts i' , secured to the pipes rigidly between the same. (See Fig. 7.) These 85 nuts are tightly clamped on the pipe-section to prevent the same from turning or partially rotating. A casing v surrounds the pipes within this spring. This coil-spring is secured to the plates t by adjustable staples t' , 90 passing through the plates and the walls of the chambers b .

Vertical coiled springs s' are located and securely fastened between the plates h' and the bottom plate t to assist in sustaining the 100 weight of the pipes a' and their attachments.

The device is shown and described as having two pipes and coupling-heads at each end of the car, the pipes being connected with radiators on opposite sides of the car, although 105 it is evident that if desirable one pipe and coupling only need be used.

The coupling connecting-heads are preferably cast integral with the curved projecting ends having the inclined flat inner faces and the socket beside the faces corresponding to the curved projection. These connections are so arranged that no matter what end of the car is coupled the connection will register with the abutting connection of the adjacent 115 car. All the parts are interchangeable, so that when any part becomes disarranged a new one may be substituted.

It is evident that various changes and modifications might be made in the form and arrangement of the parts described without departing from the spirit and scope of my invention; hence I do not wish to limit myself to the precise construction herein set forth.

What I claim is—

1. A half member of a detachable pipe connection or coupling, consisting of a hollow head on the end of a pipe-section, having a surrounding contact edge on its outer end provided with a packing-ring, a projection 130 extending forwardly from one side of said end within said contact-edge, a socket in the opposite side of said end within said edge corresponding to said projection, a flat inner

inclined contact-face formed by said projection and socket, having a port surrounded by a packing-ring, and a valve normally closing said port and automatically opened when 5 the coupling is made, substantially as described.

2. In a car-heater, the combination of the main heating-pipe extending into the car, a chamber under the car opening into the same, 10 a non-flexible longitudinally-movable pipe-section in and projecting from the end of said chamber and loosely connected with said main pipe, a connecting-head on the outer end of said section, a movable casing in said chamber 15 surrounding said section, and springs yieldingly holding said casing in its normal position in the chamber and allowing said section vertical and lateral play and holding the same in position, substantially as described.

20 3. In a car-heater, the combination, with a support beneath the car and the main heating-pipes extending into the car, of a pair of longitudinally-movable non-flexible pipe-sections located beneath the car in said support 25 and loosely connected with their respective main pipes, connecting-heads on the outer ends of said sections, a casing in said support surrounding said sections to hold and prevent independent vertical and lateral play of 30 the same, and springs yieldingly holding said casing in its normal position, whereby said sections have a united vertical and lateral play, substantially as described.

4. A half member of a detachable pipe connection or coupling, consisting of a non-flexible longitudinally-movable pipe-section and an enlarged hollow head on the outer end of the same, having a surrounding contact-edge on its outer front and provided with packing, 35 a projection extending from one side of its front end within said packing, and a correspondingly-shaped socket within said packing and in the opposite side of said front end of the head and forming with the projection

an inclined contact-face within and crossing 45 the plane of said surrounding edge, and provided with a central port surrounded by packing, substantially as described.

5. In a car-heater, the combination of the main heating-pipes of the car, a non-flexible 50 longitudinally-movable pipe-section located beneath and projecting from the end of the car, coupling sleeves and elbows connecting said section and main pipe to allow the free end of said section universal play, a connecting-head on the outer end of said section, a spring to yieldingly hold said section to its limit of outward movement, a box or casing 55 surrounding and forming a guide for said section, a support beneath the car for said casing, and springs interposed between said casing and said support to yieldingly hold said section in its normal position and allow vertical and lateral swing of the same, substantially as described. 60

6. In a car-heater, a longitudinally-movable non-flexible pipe-section loosely connected with the main heating-pipes of the car and located beneath an end of the car, and a connecting-head on the outer end of the same, 70 in combination with a spring yieldingly holding said section to its limit of outward movement, a box or casing surrounding the pipe-section to hold the same and having internal guides upon which said section slides longitudinally, a support for said box located beneath the car, and springs interposed between said support and box to yieldingly hold the same and the pipe-section in their normal 75 position and allow vertical and lateral swing of the same, substantially as described.

In testimony that I claim the foregoing as my own I affix my signature in presence of two witnesses.
